INVENTOR

UNITED STATES PATENT OFFICE.

HENRY J. JUENEMANN, OF WASHINGTON, DISTRICT OF COLUMBIA.

DESIGN FOR A BADGE, WATCH-CHARM, OR SIMILAR ARTICLE OF JEWELRY.

57,349.

Specification for Design.

Patented Mar. 15, 1921.

Application filed May 28, 1920. Serial No. 385,071. Term of patent 7 years.

To all whom it may concern:

Be it known that I, HENRY J. JUENEMANN, a citizen of the United States, residing at Washington, in the District of Columbia, have invented a new, original, and ornamental Design for Badges, Watch-Charms, and Similar Articles of Jewelry, of which the following is a specification, reference being had to the accompanying drawing, forming part thereof.

The figure is an elevation of a badge, watch charm or similar article of jewelry, showing my new design.

I claim:—

The ornamental design for a badge, watch charm, or similar article of jewelry, as shown.

In testimony whereof I affix my signature.

HENRY J. JUENEMANN.
